UNITED STATES PATENT OFFICE.

ARCHIBALD HYDE EHLE, OF PHILADELPHIA, PENNSYLVANIA, ASSIGNOR, BY MESNE ASSIGNMENTS, TO THE BALDWIN LOCOMOTIVE WORKS, OF PHILADELPHIA, PENNSYLVANIA, A CORPORATION OF PENNSYLVANIA.

INTERNAL-COMBUSTION LOCOMOTIVE.

1,018,889.

Specification of Letters Patent. Patented Feb. 27, 1912.

Application filed December 14, 1910. Serial No. 597,250.

To all whom it may concern:

Be it known that I, ARCHIBALD H. EHLE, a citizen of the United States, residing in Philadelphia, Pennsylvania, have invented 5 certain Improvements in Internal-Combustion Locomotives, of which the following is a specification.

The object of my invention is to construct a simple and practical locomotive using an 10 internal combustion engine as the motive power and gearing through which the wheels are driven, together with reverse gearing whereby the locomotive can be driven in one direction at the same number of speeds as 15 in the opposite direction.

In the accompanying drawings:—Figure 1, is a side view illustrating my internal combustion locomotive; Fig. 2, is a plan view; Fig. 3, is a sectional plan view on the 20 line 3—3, Fig. 1; Fig. 4, is a front view, and Fig. 5, is a view illustrating a modification of the driving mechanism.

A is the frame of the locomotive having pedestals in which are boxes a—a. 25 B—B' are axles mounted in the boxes and on which are the flanged wheels b—b' respectively. In the present instance the wheels are mounted on the inside of the frame and the axles project beyond the 30 frame and on each axle is a crank c; the two cranks at each side being connected by a rod C, as clearly illustrated in Fig 2. This construction is particularly adapted for narrow-gage tracks, but in wide gage tracks the 35 wheels may be on the outside of the frames, in which case the crank pins are secured directly to the wheels, as in Fig. 5. Mounted between the boxes a and the frame are coiled springs a', in the present instance, so that 40 the frame is spring supported.

D is an internal combustion engine, of any suitable type, having cylinders d, water-jacketed, as shown, and a main crank shaft D' on which is mounted the fly wheel D². 45 E is a continuation of the crank shaft and is provided with a clutch E', which is arranged to be moved into engagement with a clutch face, in the present instance on the fly wheel D². The shaft E is connected 50 through a flexible joint in turn to a shaft E², which has its bearings in the gear casing F. Secured to this shaft are two gear pinions e and e', one greater in diameter than the other, and these pinions mesh respectively

with wheels f—f', mounted loosely on an intermediate shaft G so that the gears always turn with the main shaft. On the intermediate shaft G is a clutch sleeve g. This clutch sleeve is connected to the shaft so that while it is free to slide thereon it must turn 60 with the shaft. On each end of this sleeve are clutch teeth which engage the clutch teeth on the hubs of the gear wheels f—f', and when the sleeve is in the mid position the shaft G remains idle. When the clutch 65 sleeve is moved to the rear then the shaft G is driven through the gears e and f. When the clutch is moved forward the shaft is driven through the gears e' and f'. The bearings, in the present instance, for the 70 shafts E² and G are ball bearings and I preferably extend the hubs of the gears f and f' so that they will pass through the bearings. The shaft G has a full bearing in the hubs of the said wheels. 75

On the forward end of the shaft G is a beveled pinion g', which meshes with bevel wheels H—H' on a transverse shaft I. These wheels are loosely mounted on the shaft so that when the shaft is turned the 80 wheels H and H' revolve. On the shaft I and mounted between the two wheels H and H' is a clutch sleeve h having teeth at each end which engage the teeth on the hubs of the bevel gear wheels H, H'. This sleeve is 85 splined to the shaft I so that while it is free to slide on the shaft, it must turn with it. The shaft I has its bearings in an extension F' of the gear casing so that the gearing is 90 inclosed within the casing. 90

On one end of the shaft I outside of the gear casing is a sprocket wheel i' and passing through this sprocket wheel is a chain i² which passes around a sprocket wheel i² on the axle B so that the front axle is driven 95 through the gearing and the drive chain. In some instances, I may duplicate the chain drive by mounting another pair of sprocket wheels and chain on the opposite side of the casing. 100

A' is the cab of the locomotive having, in the present instance, a seat a for the engine driver and the engine driver in this instance faces toward the opposite side of the locomotive and in front of the seat is the brake wheel J, mounted on a shaft J', connected 105 to brake mechanism J² of the ordinary type and carried by the supports for this shaft

is a throttle lever K and a spark lever L. The means of connecting these levers with the engine is of the ordinary type and need not be described in detail.

5 N is the speed control lever which shifts the clutch sleeve g , while M is the reverse control lever which shifts the clutch sleeve I. Both of these levers are located so as to be readily operated by the engine driver 10 from his seat.

P is the foot treadle which is connected by a wire rope or chain p under tension to the clutch lever p' of the main clutch E' so that when it is necessary to throw out the main 15 clutch, the treadle P is depressed.

The speed control lever N is mounted on a vertical shaft N' on which is an arm n attached to a long connecting rod n' leading to an arm n^2 on the rock shaft G' carrying 20 a forked arm g^2 which engages the sleeve g so that when the speed controlled lever N is moved motion will be imparted to the sleeve G. The reverse control lever M is mounted on a rock shaft M' which extends to the 25 forward end of the frame and on this shaft is an arm m connected by a link m' to an arm m^2 on a shaft carrying a forked arm M^2 which engages the sleeve i on the shaft I, so that on moving the reverse control 30 lever the direction of movement of the locomotive can be regulated.

On the roof of the cab in the present instance is the radiator S connected by circulating pipes to the water jacket of the engine. This radiator is made of a central section s and side sections s' connected to the central section by tubes s^2 and under the roof is the gasoline supply tank T connected by piping to the carburetor of the engine. 40 Projecting from the forward end of the cab is a hood A² which incloses the engine.

The number of speeds forward and rearward will depend upon the purpose for which the locomotive is intended.

45 By the above construction, it will be seen that I am enabled to provide for two or more changes of speed forward and two or more corresponding changes of speed rearward as it will be understood that this locomotive is especially adapted for shifting in industrial works and as the locomotive will travel in either direction the same number of speeds is necessary in going backward as in going forward.

The location of the seat of the driver is such that he has full view of the track in going in either direction and all the operating mechanism is within easy reach, giving him absolute control of the locomotive.

I claim:

1. The combination in an internal combustion locomotive, of a main frame; two axles mounted on said frame; wheels on the axles; cranks on the axles; rods connecting the cranks; an internal combustion engine mounted on the frame over the rear axle; a primary driving shaft extending from the crank axle of the engine over the forward axle of the locomotive; an intermediate shaft located in advance of the forward axle and below the main driving shaft; change gearing mounted between the two shafts; a bevel pinion on the end of the intermediate shaft; a transverse shaft; a bevel gear wheel thereon with which the pinion meshes; a chain wheel on the forward axle of the locomotive; a chain wheel on the transverse shaft; and a chain passing around the chain wheels.

2. The combination in an internal combustion locomotive, of a main frame; two axles mounted thereon; wheels on the axles; cranks also on the axles; connecting rods extending from one crank to the other on each side of the locomotive; an internal combustion engine mounted on the frame above the rear axle; a main shaft coupled to the crank shaft of the engine and extending over the front axle; an intermediate shaft located in advance of the front axle and located below the main shaft; change gearing coupling the two shafts; a bevel pinion on the end of the intermediate shaft; a transverse shaft at the forward end of the locomotive; two bevel gear wheels loose on said shaft meshing with the pinion; a clutch arranged to slide on but turn with the shaft and having teeth arranged to engage with either one of the bevel gears; a chain wheel on one end of the transverse shaft; a chain wheel on the forward axle; and a chain connecting the two wheels.

In testimony whereof, I have signed my name to this specification, in the presence of two subscribing witnesses.

ARCHIBALD HYDE EHLE.
